M. B. PEAL,

PHONOGRAPH.

APPLICATION FILED APR. 20, 1916.

1,307,020.

Patented June 17, 1919.

Marshall B. Peal Inventor
By his Attorney

S. Langford & Son, Inc.

UNITED STATES PATENT OFFICE.

MARSHALL B. PEAL, OF BROOKLYN, NEW YORK.

PHONOGRAPH.

1,307,020.

Specification of Letters Patent. Patented June 17, 1919.

Application filed April 20, 1916. Serial No. 92,564.

To all whom it may concern:

Be it known that I, MARSHALL B. PEAL, residing at Brooklyn, in the county of Kings and State of New York, have invented certain new and useful Improvements in Phonographs, of which the following is a specification.

This invention relates to a phonograph, and particularly to means for automatically causing the phonograph to cease all mechanical motion after the stylus or needle has completed its course of travel relatively to the sound producing surface of the record.

A further object is to provide a record having means adapted to coöperate with features embodied in the phonograph structure for causing the rotation of the record to cease after the sound producing surface of the record has been traversed by the stylus or needle.

A further object is to provide means for imparting relatively quick swinging movement to the phonograph arm after the stylus carrying the said arm has completed its travel over the sound producing surface of the record.

A more detailed object is to provide a continuation from the sound producing groove in the record adapted to impart a quick swinging movement to the phonograph arm after the stylus has completed its travel of the sound producing groove.

Further detailed object is to provide sufficient means for retaining the stylus against possible accidental displacement from the continuation of the sound producing groove.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown a merely preferred form of embodiment of the invention:

Figure 1 is a top plan view of a phonograph machine having a record in position thereon, provided with this invention.

Fig. 2 is a diagrammatic view illustrating the arrangement and shape of the groove of the central portion of the disk illustrated in Fig. 1.

Fig. 3 is an enlarged sectional view or development of the groove constituting one of the essential features of this invention.

Fig. 4 is a fragmentary sectional view 60 taken transverse of the groove; and

Fig. 5 is a view similar to that shown in Fig. 4, but illustrating a modification.

Referring to the drawings for a detailed description of the structure shown therein, 65 the reference character L indicates the phonograph disk. The reference character G indicates the rotatable table common to phonograph construction, and the reference character H indicates the horn arm.

The record disk is adapted to be mounted upon the table G, in the usual manner as illustrated in Fig. 1.

The table G may be rotated by any suitable mechanism from within the casing A, 75 such mechanism forming no part of this invention.

A suitable brake or "stop" mechanism is employed in connection with the table G for braking or stopping the rotation of the 80 table. This mechanism may be of any approved type now well known in the art.

The brake or "stop" mechanism illustrated is simply exemplary and comprises bell-crank lever 2, the arm being fitted with a 85 friction element 3 and the other arm being engaged by a tension spring 4 and normally urging the friction element toward the periphery of the table G. A second bell-crank lever is arranged adjacent to the first 90 and has one of its arms, as 5, formed with a hook, and engaging the end of one arm of the first bell-crank lever to hold the friction element out of engagement with the table G. The spring 4 is fixed to the arm 5 to urge 95 the same into an engaging position. The arm 6 of the second bell-crank lever projects into the path of movement of a lug 7 formed upon the horn H, so that when said horn swings inwardly the lug 7 will engage 100 the arm 6 and move the same to permit the friction element 3 to press against and stop rotation of the table G.

The use of a lug, or the like, carried by the horn arm for engaging a lever to trip a 105 brake mechanism is well known, but heretofore a minute and careful adjustment has been necessary as between the lug and lever so as to cause the same to properly co-operate in stopping rotation of the disk at 110 the proper point. It has been necessary in most cases to change the adjustment for each

and every record played. In some of the best known devices of this character it has even been necessary to make a readjustment of the parts for each piece played by the machine 5 irrespective of whether the record is changed or not.

By the present invention, however, no such adjustments are required. When using a record having this invention applied there-
10 to, the horn arm will be given an accelerated swinging movement just after the music surface of the disk has been traversed. The movement will be through such a sufficiently wide arc so that the lug 7 will engage and
15 operate the arm 6 irrespective of the precise position of the arm 6 with respect to the lug 7.

The means devised for accomplishing this result is best illustrated in the diagrammatic view Fig. 2. It consists of a continuation groove 8 from the innermost convolution of the music groove. The said continuation is made on a curve of gradually diminishing radii. The decrease in radii, however, being
25 much greater than the decrease in radii of the normal music groove. Preferably, approximately one turn, or less, of the disk only is required to carry the continuation from the innermost music groove to the in-
30 nermost point reached by the continuation.

Thus if the stylus, as 10, carried by the horn arm has completed its travel of the music groove, approximately one more turn of the disk will guide the stylus rapidly in-
35 wardly to its innermost desired position.

In Fig. 1 the light dotted lines indicate the angle defined from the center of movement of the horn arm in one direction to the stylus and in another direction to the end 40 of lug 7. The heavy dotted lines indicate the position of this angle when the stylus has completed its travel of the music groove, (note that the arm 6 of the bell-crank lever has not yet been reached by the lug 7). The
45 heavy dash line indicates the position of the angle after the disk has made approximately one more revolution. (Note that the lug 7 has passed through the region of the arm 6 to a sufficient extent to have caused the oper-
50 ation of said arm.)

In order that the stylus will be caused to travel correctly and easily along the continuation 8, it is part of this invention to provide means for retaining the stylus 55 against possible displacement from the groove forming said continuation. This means includes two distinct elements.

First, the idea of so curving the groove that the accelerated swing of the stylus and
60 horn will begin very gradually and will not assume marked proportions until after a sufficient momentum has been gathered in the horn arm. Thus, approximately the first quarter of the continuation groove is on
65 almost the same curve as the curve of the

music groove, the radii gradually reducing toward the inner end. The second quarter is of only slightly more rapidly reducing radii. The third quarter is of more rapidly reducing radii than the second quarter. The 70 fourth quarter, which will not be reached until a considerable momentum has been gathered in the stylus supporting parts, is on a very much more rapidly reducing radii than either of the previous quarters. Of course the change from one quarter to the next is gradual and smooth, as clearly indicated in Fig. 2.

Second, the idea of making the continuation groove of varying depths in accordance 80 with the resistance required to prevent displacement of the stylus at the successively advancing portions of said groove. This changing depth is clearly indicated in the development of Fig. 3. At the right hand side 85 of said figure the space between A and B corresponds with the space between the same letters in Fig. 2. The groove in this portion is of substantially the same depth as the music groove. The space between the letters 90 B and C corresponds with the space between the same letters in Fig. 2. The inward movement of the stylus begins to be accelerated in this space and accordingly, the groove is gradually deepened until at C it reaches its 95 maximum depth. From C to D the inward movement of the stylus is gradually accelerated and a certain degree of momentum is picked up, so that the depth of the groove may be gradually diminished, as indicated. 100

As above stated, the throw or swing of the horn from the position shown by the heavy dotted lines in Fig. 1 to the position shown by the heavy dash lines in said figure, is intended to operate the automatic stop 105 mechanism. At 11 in Figs. 1 and 2, however, a groove is illustrated which is adapted to receive the stylus in case the automatic stop should for any reason not operate. Groove 11 is circular so that the stylus would 110 continue to traverse the same without swinging the horn until the rotation of the disk was stopped.

The depth of the groove 11 is preferably constant, as shown between the letters D and 115 E in Fig. 3.

In Fig. 5 a modification is illustrated in which an embankment 12 is shown as a substitute for deepening the groove. The embankment is arranged to receive lateral pressure from the stylus in the same manner as would the walls of a deepened groove. The actual depth of the groove in this instance may be maintained the same as the normal music groove, if desired. Or the embankment 120 125 may be employed in connection with the deepened groove if preferred.

Record disks provided with a continuation groove, as above described, may be employed on any of the usual types of disk 130

phonographs, and will operate to control the automatic stops of such machines without necessity for adjustment of any of the parts of such automatic stops.

5 Although it is preferable that the extension 8 be made directly in the material of the disk in the same manner as are the ordinary music grooves, nevertheless, it will be obvious that a sheet of material might read-
10 ily be pasted, or otherwise attached, to the disk, and said sheet be provided with the groove 8, if desired. This method may be employed to some advantage in connection with the records which have already been
15 manufactured in the usual manner.

As many changes could be made in this construction without departing from the scope of the following claims, it is intended that all matter contained in the above de-
20 scription or shown in the accompanying drawing shall be interpreted as illustrative only and not in a limiting sense.

Having thus described my invention what I claim as new and desire to secure by Let-
25 ters Patent is:

1. A phonograph record disk having the usual convolute music groove therein for receiving the stylus, said disk being formed with an inwardly projecting extension groove
30 continuing from the inner end of the music groove also for the travel of the stylus substantially for the purpose set forth, the extension groove being also convolute but being curved on a more rapidly reducing radii
35 within the radii of successive portions of the music groove so as to accelerate the inward

movement of the stylus, the portion of the length of the extension groove adjacent the inner end of the music groove being of abruptly increasing depth in a direction away 40 from the inner end of the music groove, and the remaining portion of the length of the extension groove being of gradual decreasing depth inwardly to the inner end of the extension groove, for the purpose described. 45

2. A phonograph record disk having the usual convolute music groove therein for receiving the stylus, said disk being formed with an inwardly projecting extension groove continuing from the inner end of the music groove also for the travel of the stylus substantially for the purpose set forth, the extension groove being also convolute but being curved on a more rapidly reducing radii than the radii of successive portions of 50 the music groove so as to accelerate the inward movement of the stylus, and means embodied in the form and disposition of said extension groove relatively to the music groove effective to prevent accidental disengagement of the stylus from the extension groove in proportion to the tendency of the stylus to leave the extension groove at successive points in the length of the extension groove. 55

In testimony whereof I affix my signature in the presence of two witnesses.

MARSHALL B. PEAL.
